METHOD OF MAKING DRY CELLS

Howard B. Hileman, Lancaster, Ohio, assignor to
Ray-O-Vac Company, a corporation of Wisconsin

Application September 6, 1940, Serial No. 355,677

8 Claims. (Cl. 136—175)

This invention relates to a dry cell and method of making the same, and more particularly to a method of preparing the dry cell core and assembling the cell.

The primary object of the invention is to provide a simple, inexpensive and efficient method of making and assembling dry cells. Another object of the invention is to provide for the treatment of dry-cell cores to prevent disintegration thereof in the process of assembling the units. Still another object is to provide a method of treating the dry-cell cores whereby the same may be readily and easily handled.

Another object is to solidify and bond together the entire mass of a dry cell core into an integral unit which is highly resistant to disintegration. Yet another object is to provide a solid unified core wherein the mass thereof is bonded together by the freezing of the moisture therein.

Other features and advantages will appear from the following specification and drawing, in which—

Fig. 1 is a vertical sectional view of a dry-cell core; Fig. 2 is a similar view of a casing for a dry cell, the casing being provided with fluid electrolyte in the lower portion thereof; Fig. 3 is a vertical sectional view of a dry cell with the core in position in the casing; and Fig. 4 is a plan view of the assembled unit.

Heretofore in the making and assembling of dry cells, the handling of the core has been a difficult problem. The core normally consists of a carbon pencil electrode with a granular depolarizing mixture distributed thereabout, the depolarizing mixture being compressed into a suitable shape. Since the depolarizing mixture is an electrical conductor, the disintegration thereof may readily cause a short circuit to be formed in the cell. For example, when the core is inserted into the casing, any particles which break or fall from the core may lodge in the electrolyte paste and cause such a short circuit.

Various means have been developed for avoiding this difficulty. In some instances, the core has been wrapped in cheesecloth, muslin, or other suitable material. This operation is obviously expensive.

It has also been suggested that the core be inserted into the casing before the electrolytic paste is added. However, the pouring of the paste around the core after the same is in position is a difficult operation, and, in addition, tends to wash particles of the core into the paste.

Another means which has been used in an effort to avoid the difficulty of handling the core is

to place a lining in the zinc cup casing, the lining being made of paper and being saturated with the electrolytic paste. The depolarizing mixture is then placed in the lined casing and the carbon electrode inserted in the center thereof. This method, although it avoids the problem of disintegration of the core, does not provide an entirely satisfactory cell.

This invention includes broadly the subjecting of a moist core to a temperature substantially below 32° F. until it is frozen and substantially the entire mass thereof solidified. The frozen core may be readily handled without danger of disintegration or breaking off of particles therefrom.

In the specific embodiment of my invention described herein, a core 10 includes an electrode 11 and a depolarizing mixture 12 distributed about the electrode. The electrode 11 is preferably of the usual carbon composition.

The depolarizing mixture 12 may be composed of any suitable mixture of the type ordinarily used for this purpose. The usual composition includes a mixture of graphite, manganese dioxide, sal ammonic (ammonium chloride), and a viscous solution of zinc chloride. The first three ingredients as normally used in the dry cell are in granular form, while the zinc chloride is used in the form of a water solution, preferably of a specific gravity of 55° Bé. The term "granular" will be understood to include powdered or even colloidal particles. In any event, the mixture should contain a substantial quantity of moisture preferably between 5 and 35%.

In accordance with the usual practice in the art, the depolarizing mixture may be placed in a mold (not shown) and compressed by the exertion of pressure thereon. The carbon electrode is then inserted in the mixture to form a complete core.

After the core is formed, it may be subjected to a temperature substantially below 32° F. and maintained at this temperature until the mixture therein is frozen. Because of the presence of water-soluble salts in the depolarizing mixture, it may be necessary to lower the temperature several degrees or more below 32° F. in order to accomplish the freezing.

Any suitable apparatus may be used for the freezing operation. For example, the cores may be placed in any of the well known mechanical refrigerators. Preferably the refrigerating apparatus is arranged to provide a temperature well below the freezing temperature in order to speed up the operation. Thus a temperature of —30°

F. has been found to be very satisfactory in practice.

The temperature necessary to freeze the core will, of course, vary with the composition and moisture content of the depolarizing mixture. Since the soluble electrolytes or salts in the depolarizing mixture reduce the freezing point of the solution, the temperature required for freezing will be lower as the concentration of the solution increases. Thus when only a small percentage of moisture is present, the freezing point will be relatively low. Similarly, when the percentage of soluble electrolytes in the composition is increased, the freezing point will be further lowered.

Although water is normally used in the depolarizing mixture, it is possible under some conditions to use other solvents. Accordingly, by referring to moisture in the mixture, I mean to include any liquid present therein which can be frozen to bond the mixture into an integral mass.

When the core is cooled to freeze the same, the depolarizing mixture becomes a substantially entire solid mass. The frozen moisture in the core serves to bond the particles thereof together. Since the moisture is distributed substantially uniformly throughout the depolarizing mixture, the bonding action causes the core to be retained in its original shape as an integral mass which is highly resistant to disintegration.

The frozen cores may be readily and easily handled. It is no longer necessary to take extreme precautions to prevent disintegration of the core or the falling or breaking off of particles therefrom. Where processes heretofore used have required careful hand operations in assembling the cells, it is now possible to mechanize these operations.

A casing or shell 13 is provided to receive the core. This casing should be of an electrically conducting material such as a suitable metal, and is preferably in the form of a cylinder provided with a closed bottom 14.

Within the casing may be placed a suitable quantity of a fluid electrolyte 15. The composition of such electrolytes is well known in the art and need not be described herein. The electrolyte is preferably viscous in character and may be of the consistency of paste. The purpose of the fluid electrolyte is to provide an electrolytic medium between the conducting casing 13 and the core 10.

When the cell is to be assembled, the frozen core 10 is inserted into the casing 13 and into the fluid electrolyte 15 in the lower portion thereof. As the core is inserted into the electrolyte, the electrolyte wells up around the sides of the core and along the inner surface of the casing until (Fig. 3) the electrolyte forms a layer 16 around substantially the entire cylindrical sides of the depolarizing mixture of the core 10. By freezing the core before inserting it into the casing, substantially all danger of having particles break off from the core and fall into the electrolyte is avoided.

Other methods of assembly may, of course, be used if desired. For example, the core may be inserted into the casing before the electrolyte is placed therein. The electrolyte may then be poured into the casing between the core and the casing. In either event, and regardless of the method of assembly, there is practically no danger of particles falling or washing off into the electrolyte.

In the making of dry cells for special types of

service, it is desirable to have a construction in which the core is as large as possible with respect to the size of the cell. A large core permits the use of a large amount of depolarizing material and produces a more efficient cell. By freezing the core and eliminating the danger of disintegration thereof, it is now possible to use a larger core with the same casing. This is possible because the distance between the core and the casing need not be so great in order to permit ready assembly of the cell. The diameter of the core, therefore, may be only slightly less than the inside diameter of the casing.

The freezing of the core also provides certain advantages in the handling of the assembled cell. The frozen depolarizing mixture clings more firmly to the electrode inserted therein. Accordingly, operations on the assembled cell may be carried out without taking extreme precautions to prevent the displacement or loosening of the electrode within the depolarizing mixture.

The invention is also useful in making what is known in the trade as "flat type" batteries, where the carbon electrode is flat and the depolarizing mix is in the form of a flat panel, of a desired thickness which is handled separately. Freezing the mix makes the panel much less fragile and it is accordingly easy to handle. By the present invention, a depolarizing mix may be used having a much higher percentage of moisture than has heretofore been considered practical.

The foregoing specific examples have been given for the purpose of illustrating the invention and the means of practicing it. Changes and modifications may, therefore, be made in the method and product as described, particularly with respect to the composition of the various portions of the battery and in connection with the conditions and order of the various steps of the method, without departing from the spirit and scope of my invention as set forth in the appended claims.

I claim:

1. In a method of making dry cells, the steps of providing a solid electrode in contact with a moist depolarizing mixture in a predetermined shape, subjecting the mixture to a temperature below 32° F. to freeze the mixture in said shape, and placing the assembly in a dry cell unit.

2. In a method of making dry cells, the steps of providing a casing and a core, said core including an electrode packed in a moist, granular, depolarizing mixture, subjecting said core to a temperature substantially below 32° F. to freeze the assembly, and inserting the frozen core into said casing.

3. In a method of making dry cells, the steps of providing a casing and a core, said core including a moist, granular, depolarizing mixture compressed in a predetermined shape packed around an electrode, subjecting said core to a temperature substantially below 32° F. for a sufficient period of time to freeze said mixture in said shape, and inserting the frozen core into said casing.

4. A method of making dry cells comprising providing a casing and a core including an electrode, said casing having therein an electrolytic material, freezing said core by subjecting the same to a temperature substantially below 32° F., and picking up the core by means of the electrode and inserting it into said casing, said core being separated from said casing by said electrolytic material.

5. A method of making dry cells comprising providing a casing, a core with an electrode, and a fluid electrolyte in said casing, subjecting said core with its electrode to a temperature substantially below 32° F. for a sufficient period of time to freeze the same, and inserting the frozen core into the casing and into the fluid therein to cause said fluid to well up between the casing and the core.

6. A method of making dry cells comprising providing a cylindrical casing having a closed bottom, a core, and a fluid electrolyte in the lower portion of said casing, said core including a moist, granular, depolarizing mixture compressed in the form of a cylinder around an electrode, the diameter of the core being slightly less than that of the casing, cooling the core to freeze the same, and inserting the frozen core into the

casing and into the fluid in the lower portion thereof to cause the fluid to flow upwardly between the core and the casing.

7. A method of making dry cell cores for assembly in batteries, comprising distributing a moist depolarizing mixture around an electrode in a predetermined shape, and freezing the same to form a solid integral core prior to its assembly in a dry cell.

10. A method of preparing dry cell cores for assembly in batteries, comprising compressing a moist depolarizing mixture around an electrode in a predetermined shape, and freezing the compressed product to solidify substantially the entire mass thereof in the form of a solid integral core prior to its assembly in a cell.

HOWARD B. HILEMAN.
